STANDUP MIRROR

Philip J. O'Brien, Ashby, Mass., assignor to Standard Pyroxoloid Company, Leominster, Mass., a corporation of Massachusetts

Filed May 23, 1963, Ser. No. 75,027

Term of patent 14 years

(Cl. D86—10)

FIG. 1

FIG. 3

FIG. 1 is a view in front elevation of a standup mirror showing my new design;

FIG. 2 is a view in side elevation showing the stand closed; and

FIG. 3 is a similar view showing the stand open. The reverse side is the same in appearance as FIG. 1. The essential features of my design reside in the overall appearance of the combined mirror and stand, and particularly in the appearance of the lower portion of the stand in its relation to the lower portion of the mirror, wherein the lower portion of the base of the stand is flat, the upper portion is spaced from the lower curved portion of the mirror and is reversely curved with reference thereto, and the side arms of the frame are curved inwardly toward the mirror and then outwardly, all as shown.

I claim:

The ornamental design for a standup mirror, as shown and described.
